FIG. 4 is a reverse side view of the gearbox of FIG. 1;
FIG. 5 is a front perspective view of the gearbox of FIG. 1;
FIG. 6 is a rear view of the gearbox of FIG. 1;
FIG. 7 is a top view of the gearbox of FIG. 1;
FIG. 8 is a rear perspective view of the gearbox of FIG. 1;
FIG. 9 is a side view illustrating the ornamental features of the gearbox of FIG. 1;
FIG. 10 is a front view of the gearbox of FIG. 1;
FIG. 11 is a bottom view of the gearbox of FIG. 1;
FIG. 12 is a reverse side view of the gearbox of FIG. 1;
FIG. 13 is a front perspective view of the gearbox of FIG. 1;
FIG. 14 is a rear view of the gearbox of FIG. 1;
FIG. 15 is a top view of the gearbox of FIG. 1; and,
FIG. 16 is a rear perspective view of the gearbox of FIG. 1.
The broken lines shown in FIGS. 9-16 show unclaimed environment of the claimed design.
